UNITED STATES PATENT OFFICE.

RAY C. NEWHOUSE, OF CHICAGO, ILLINOIS, ASSIGNOR TO ALLIS-CHALMERS MANUFACTURING COMPANY, OF MILWAUKEE, WISCONSIN, A CORPORATION OF DELAWARE.

COMMINUTOR.

Application filed April 24, 1926. Serial No. 104,298.

This invention relates in general to improvements in the art of comminuting materials, and relates more specifically to improvements in the construction and operation of rotary drum mills wherein a plurality of freely tumbling rods are caused to cooperate with the drum liners to granulate substances such as rock, ore, clinker, coal or the like.

10 An object of the invention is to provide an improved rod mill which is simple in construction and efficient in operation.

It is common commercial practice to utilize freely tumbling rods, as granulators in drum mills wherein the raw material is fed into one end of the drum and the reduced material is delivered from the opposite end of the drum. In these prior rod mills the entering material comprises pieces of relatively large size which are gradually reduced throughout the length of the mill and are discharged as pieces of much smaller average size. By admitting the coarse material to one end of the rods and delivering the fine material from the opposite ends thereof, the rods are naturally spaced further apart near the feed end, and do not retain a desired parallel relationship, thus causing the rods to wear unevenly and hindering the discharge of final product.

In order to overcome this defect of the prior rod mills and to maintain the rods parallel to each other at all times, the present invention contemplates admission of the raw material to the center of the mill and discharge of fine material from the opposite ends thereof. This arrangement of the elements not only maintains the rods parallel to each other in order to distribute the wear thereon, but also enhances the capacity of the mill and improves the effectiveness of the rods by permitting rapid escape of the relatively fine material which tends to cushion the impact of the cascading rods.

45 A clear conception of an embodiment of the invention and of the operation of a mill constructed in accordance therewith, may be had by referring to the drawing accompanying and forming a part of this specification in which like reference characters designate the same or similar parts in the various views.

50 Fig. 1 is a somewhat diagrammatic central longitudinal section through an improved rod mill.

Fig. 2 is a somewhat diagrammatic enlarged transverse vertical section through the inlet portion of the improved rod mill.

The improved rod mill disclosed herein comprises in general a cylindrical drum 2 having liners 15 and end heads 3, 4 which provide a granulating chamber 10 bounded by straight line generatrices and having uniform diameter throughout its length. The medial portion of the drum 2 is provided with a pair of spiral feed supply scoops 8 cooperating with a receptacle 9 to receive material and formed to deliver this material into diametrically opposite inlet openings in the medial portion of the chamber 10, as the mill revolves. The scoops 8 may be shielded by means of a housing 14 and the material may be admitted to the receptacle 9 through a supply opening 13. The opposite ends of the mill are provided with trunnions 5 and 6 forming supports for the mill, and providing end discharge openings of smaller diameter than the internal diameter of the drum 2. A plurality of freely tumbling granulating rods 11 are located within the chamber 10 and in the embodiment shown, the chamber 10 is partially filled with liquid 12. The drum 2 may be rotated by means of a driving gear 7 in a well known manner.

55 During normal operation of the mill, the drum 2 is being rotated continuously, thus causing the scoops 8 to intermittently remove batches of raw material from the receptacle 9 and to deliver the raw material through the inlet openings in the medial portion of the periphery of the drum 2. The material thus admitted is subjected to the granulating action of the cascading rods 11 cooperating with the liners 15, and advances in opposite direction toward the discharge openings in the end trunnions 5, 6. As the material is sufficiently reduced, it is eventually discharged at the opposite ends of the mill in substantially equal quantities.

60 It will be apparent that by admitting the raw material to the medial portions of the chamber 10 and of the rods 11, the rods 11 will be maintained in substantially parallel relationship at all times. Such medial admission of the material furthermore produces uniform wear on the rods 11 and by delivering material from both ends of the granulating rods, the capacity of the mill is materially enhanced since the comminuted

material is capable of more freely escaping through the pair of discharge openings than if a single discharge opening at one end of the mill is provided. While the invention is 5 shown herein as being applied to a wet grinding mill, its application to a dry grinding mill must be apparent.

It should be understood that it is not desired to limit the invention to the exact 10 tails of construction and operation herein shown and described, for various modifications within the scope of the claims may occur to persons skilled in the art.

It is claimed and desired to secure by Letters Patent:

1. In combination, a rotary drum forming a granulating chamber the inner wall of which has straight line generatrices throughout its length, means for feeding 20 material into a medial portion of said chamber through the periphery of said drum, means for discharging material from the opposite ends of said chamber, and a plurality of freely tumbling granulating rods extending substantially throughout the length of said drum.

2. In combination, a rotary drum forming a granulating chamber bounded by a cylindrical surface of uniform diameter 30 throughout its length, means for feeding material into a medial portion of said chamber through the periphery of said drum, means for discharging material from the opposite ends of said chamber, and a plurality of freely tumbling granulating rods extending 35 substantially throughout the length of said chamber.

3. In combination, a rotary drum forming a granulating chamber the inner wall of 40 which has straight line generatrices throughout its length, a spiral scoop for feeding material into a medial portion of said chamber through the periphery of said drum, means

for discharging material from the opposite ends of said chamber, and a plurality of 45 freely tumbling granulating rods extending throughout the length of said drum.

4. In combination, a rotary drum forming a granulating chamber bounded by a cylindrical surface of uniform diameter 50 throughout its length, a spiral scoop for feeding material into a medial portion of said chamber through the periphery of said drum, means for discharging material from the opposite ends of said chamber, and a 55 plurality of freely tumbling granulating rods extending substantially throughout the length of said chamber.

5. In combination, a rotary drum having opposite constricted end discharge openings 60 and forming a granulating chamber bounded by a cylindrical surface of uniform diameter throughout its length, means for feeding material directly into a medial portion of said chamber through the periphery 65 of said drum, and a plurality of freely tumbling granulating rods extending substantially throughout the length of said chamber.

6. In combination, a rotary drum forming 70 a granulating chamber bounded by a cylindrical surface of uniform diameter throughout its length, a spiral scoop rotatable with said drum to feed material into a medial portion of said chamber through the periphery 75 of said drum, hollow end trunnions for supporting said drum and providing discharge openings of less diameter than said chamber at the opposite ends of said drum, and a plurality of freely tumbling granulating rods extending substantially throughout the length of said chamber. 80

In testimony whereof, the signature of the inventor is affixed hereto.

RAY C. NEWHOUSE.
